UNITED STATES PATENT OFFICE

RAYMOND C. PIERCE, OF BRONXVILLE, NEW YORK, ASSIGNOR TO GENERAL AMERICAN TANK CAR CORPORATION, OF CHICAGO, ILLINOIS, A CORPORATION OF WEST VIRGINIA

METHOD OF MANUFACTURING TANK CARS

Application filed March 25, 1929. Serial No. 349,858.

My invention relates more particularly to the provision of means for anchoring the tank to the car underframe especially in the case of high pressure tank cars.

One of the objects of my invention is to provide against the possibility of leakage of the contents of the tank at that portion of the anchorage means therefor which is connected with the tank, and to avoid the use of rivets for holding such anchoring portion in place, the use of rivets being especially objectionable where the contents of the tanks are such as to produce corrosion of the rivets, and requiring when used the sealing thereof against contact with the tank-contents, by plates covering the rivets and sealed to the tank shell.

Another object is to provide for the rigid and secure attachment of anchors to tanks by the forge-welding method without weakening the tank structure.

Another object is to provide anchorage means which, while maintaining the tank against longitudinal movement on the underframe, will be yieldable under substantially vertical stresses, particularly for the purpose of lessening strain on the anchorage; and other objects as will be manifest from the following description.

Referring to the accompanying drawings: Figure 1 is a view in side elevation of a tank car embodying my improved anchorage means and constructed in accordance with my improved method.

Figure 2 is a vertical cross sectional view through the middle of the tank of Fig. 1 showing the latter in the process of construction of the anchorage means therefor.

Figure 3 is a plan sectional view taken at the line 3 on Fig. 2 and viewed in the direction of the arrow.

Figure 4 is a view like Fig. 2 and of the construction therein shown, representing a still further step in the process of forming the anchorage means.

Figure 5 is a view like Fig. 4 and of the construction therein shown showing the anchorage means on the tank in finished condition.

Figure 6 is a perspective view of the plate-

like flange or tongue equipped member which, in accordance with my invention, is welded to the shell of the tank to form the anchor element thereof.

Figure 7 is an enlarged broken sectional view taken at the line 7 on Fig. 1 and viewed in the direction of the arrow showing a detail of the anchoring means.

Figure 8 is a view in side elevation of the anchoring element of Fig. 6.

Figure 9 is a view like Fig. 7 of another construction of anchoring means for the tank.

Figure 10 is a view in side elevation of the plate-like anchoring element which is united with the shell of the tank to form the anchorage element shown in Fig. 9.

Figures 11 and 12 are views like Fig. 7 showing still other forms in which the anchorage may be provided in accordance with my invention; and

Figure 13, a view in side elevation of the anchor element to be united with the tank to produce the anchor construction shown in Fig. 12.

Referring first to the anchor construction illustrated in Figs. 1 to 7, inclusive, and to the method of constructing the tank with such anchorage means, the particular type of car shown in these figures of the drawings comprises an underframe structure of the center sill type represented at 14, a tank 15 superposed thereon, and means represented generally at 16 for anchoring the tank substantially midway between its ends to the center sill of the underframe 14, the ends of the tank being supported in a manner to permit of the longitudinal movement thereof in contracting and expanding.

In manufacturing the car in accordance with my invention I cause the wall of that portion of the tank shell which in the finished tank construction is the portion thereof at which the anchorage means are located (in the particular construction shown is the central portion of the tank shown) to contain an opening which in the particular construction shown is located at the bottom of the shell, extends lengthwise of the tank structure and is represented at 17, this opening by preference being of substantially rectangular form.

The anchor-forming element for the tank of Figs. 1 to 8, inclusive, is illustrated in Figs. 6 and 8, this member comprising a plate-like portion 18 of a width and length slightly greater than the width and length of the opening 17 in the tank and preferably of slightly greater thickness than the wall of the tank, the portion 18 being preferably of curved shape in cross section with its marginal edges deflected slightly upwardly as represented at 18^a, the plate portion 18 having integrally formed therewith a fin or flange 19 extending lengthwise thereof and substantially midway between the sides of the plate portion 18 and short of the ends of the latter, as shown.

In the process of producing the tank anchor the anchor element referred to is positioned in the opening 17 to oppose at the marginal edges of the plate portion 18 the inner surfaces of the marginal edge portions of the opening 17 with an overlap equal, preferably, to substantially the thickness of the tank shell, substantially as shown, with its fin 19 projecting outwardly through the opening 17 as shown in Fig. 4 in which position it is preferably electrically tack-welded in place to hold it temporarily.

The relatively overlapping portions of the anchor element of Figs. 6 and 8 and the tank are then united by forge-welding them together as by a rolling or hammering action, following the heating to the desired degree of these overlapping portions, the resultant structure being that illustrated in Figs. 5 and 7. The anchor element referred to thus closes the opening 17 in the shell and becomes firmly united to the metal of the shell for resisting the stresses imposed thereon in service.

As is well known in the metal-working art it is necessary, as a preliminary to the forge welding operation usually performed by the rolling or hammering of the parts to be united, that the opposing surfaces of the lapped parts to be united be heated to a temperature closely approaching that of the melting temperature of the material of which these parts are formed, such heating of the parts being rendered possible by reason of the lapping of these parts at an opening in the tank shell and the accessibility of these parts to the application of heat thereto both internally and externally of the tank, the deflecting of the plate portion 18 at 18^a being desirable as it enhances accessibility of the heat to the joint between the opposing edges of the tank shell and plate-portion 18.

The depending fin or flange 19 serves as a means by which the tank may be anchored in place on the underframe. In the particular construction now being described the fin 19 is shown as secured, as by rivets 20, to the vertically flanged portions 21 of plates 22 between which the fin 19 extends, the plates 22

being riveted along their outer edges to the center sill 23 of the underframe 14.

The construction shown in Fig. 9 involves the forming of the tank shell 15 with an anchor element in accordance with the procedure above described, the anchor member of this construction to be united with the shell being shown in Fig. 10 and being of the same construction as the anchor shown in Fig. 8, except that its plate portion is depressed slightly between its ends to produce a sump-forming recess 24, the metal of the depending fin portion of the anchor element where it opposes the recess 24 being cut away as represented at 25.

In this particular construction the elements which cooperate with the sectional fin-portion 19 comprises plates 26 connected at their outer horizontal portions 27 with the center sill structure 23 as by the rivets 28, their inner ends being bent to provide upwardly extending substantially vertical portions 29 between which the fin-sections 19 are embraced and to which they are held as by rivets represented at 30, the portions 27 and 29 of the plates 26 being connected together by downwardly bowed portions of these plates as shown.

The plates 26 are preferably of substantially the same length as the anchor element shown in Fig. 10 and when secured to this anchor element and the center sill structure as shown serve to effectually resist lengthwise movement of the tank as in the case of the construction shown in Fig. 1, but in addition, by reason of the slight flexibility of the bowed portions 31 of the plates 26, furnish a yielding support for the tank permitting of slight vertical relative movement of the tank and underframe and of particular importance in lessening stresses upwardly against the tank anchor under impacts to which the underframe is subjected in use.

The construction now being described also preferably comprises means resisting deflection of the anchoring means in a direction crosswise of the tank, these means comprising plates 32 held in place at their outer edges by the rivets 28 and extending inwardly to a position in which their inner edges oppose the vertical portions 29 of the plates 26 thereby forming abutments for resisting lateral deflection of the anchoring means.

The construction shown in Fig. 11 and the method of producing the same is the same as in the case of the construction shown in Figs. 1 to 7, inclusive, except that instead of providing the anchoring element of the form shown in Figs. 6 and 8 an anchoring element of the form shown in Fig. 10 is employed.

Referring to the construction shown in Figs. 12 and 13 the anchoring element of the tank instead of providing a fin for attachment to the underframe by means of other elements such as the plates 22 or 26 of the constructions of the preceding figures, is

formed integrally with a bottom plate portion at which it is attached to the center sill. The anchor element of this construction to be united with the tank shell as described in 5 the construction shown in Figs. 6 and 8, is represented at 33, its upper plate-like portion, curved in cross section and corresponding with the plate portion 18 of the anchor element of the preceding figures, being represented at 34 and its fin at 35, this fin being 10 integral with a lower plate portion 36 and disposed between the longitudinal edges of the plate portion 36 as shown.

While I have illustrated and described my 15 invention in connection with constructions in which the anchor-forming elements of the tanks are applied at their plate portions to the interior of the tank shells to oppose the inner surfaces of the marginal edges of the 20 tank openings and force welded in such position, it will be understood that if desired the anchor-forming elements may be applied at their plate portions to the apertured portions of the tank shells to oppose the outer surfaces 25 of the marginal edges of the tank openings and where the plate portions are formed with deflections such as those indicated at 18^a, these same deflections may be provided, or if desired, the deflections may extend in the 30 opposite direction.

Furthermore, other changes and alterations may be made in the construction shown and the invention embodied in other forms 35 of structure and my improved method practiced in the production of other forms of structures, without departing from the spirit of my invention.

What I claim as new, and desire to secure by Letters Patent, is:

40 1. The method of manufacturing anchor-equipped tanks which consists in forming an opening in the wall of the tank shell, positioning at said opening a member which is to form the anchor with portions thereof in 45 lapped relation to the surrounding wall of said opening and forge-welding together said lapping portions of said shell and member.

2. The method of manufacturing anchor-equipped tanks which consists in forming an 50 opening in the wall of the tank shell, positioning at said opening a member which is to form the anchor with portions thereof in lapped relation to, but throughout the greater portion of their area out of contact with, the surrounding wall of said opening and 55 forge-welding together said lapping portions of said shell and member.

3. The method of manufacturing anchor-equipped tanks which consists in forming an 60 opening in the wall of the tank shell positioning in said opening a member which is to form the anchor with portions thereof in lapped relation to the inner surfaces of the 65 surrounding wall of said opening and forge

welding together said lapping portions of said shell and member.

4. The method of manufacturing anchor-equipped tanks which consists in forming an 70 opening in the wall of the tank shell, positioning an anchor and closure-forming member at said opening, and welding together the adjacent surfaces of said member and said shell at said opening.
